WHEEL BLOCK

Marion C. Wilson, Hammond, Ind., assignor to Calumet Steel Castings Corporation, Hammond, Ind., a corporation of Indiana

Application April 8, 1957, Serial No. 45,638

Term of patent 14 years

(Cl. D41—1)

FIG. 1

I claim:

The ornamental design for a wheel block, as shown.
